[57] **CLAIM**

The ornamental design for a combined motorcycle
handle bar handgrip and brake lever unit, as shown and
described.

DESCRIPTION

FIG. 1 is a side elevational view of a combined motor-
cycle handle bar handgrip and brake lever unit showing
my new design.

FIG. 2 is a top plan view thereof.

FIG. 3 is a side elevational view thereof opposite to that
shown in FIG. 1.

FIG. 4 is a front elevational view thereof.

FIG. 5 is a bottom plan view thereof.

FIG. 6 is a rear elevational view thereof.

FIG. 7 is a side elevational view of a combined motor-
cycle handle bar handgrip and brake lever unit showing
a second embodiment of my new design.

FIG. 8 is a top plan view of FIG. 7.

FIG. 9 is a side elevational view opposite to that of
FIG. 7.

FIG. 10 is a front elevational view of FIG. 7.

FIG. 11 is a bottom plan view of FIG. 7.

FIG. 12 is a rear elevational view of FIG. 7.
